UNITED STATES PATENT OFFICE.

LUDWIG HIRSCH, OF NEW YORK, N. Y.

RULE AND SQUARE.

SPECIFICATION forming part of Letters Patent No. 329,555, dated November 3, 1885.

Application filed April 10, 1884. Serial No. 127,278. (No model.)

To all whom it may concern:

Be it known that I, L. HIRSCH, of New York, in the county of New York and State of New York have invented a certain new and 5 useful Improvement in Rules and Squares, of which the following is a specification.

My improvement consists in a rule and square composed of two limbs, which are made of any suitable material, and are rectangular 10 at their free ends. Said limbs are marked on one or more of their sides or edges with a scale of inches, and have parallel sides throughout their lengths, their meeting ends extend obliquely to their lengths, and are connected 15 by a hinge, whereby they may be folded one over another or swung out into the same plane at right angles to each other.

In the accompanying drawings, Figure 1 is an edge view of a rule and square embodying my improvement and showing the device as folded; and Fig. 2 is a plan or face view of the rule and square with the limbs extended out into the same plane. Fig. 3 is a view of the joint, showing the structure of the hinge 25 and pintle.

Similar letters of reference designate corresponding parts in all the figures.

The rule and square is composed of two limbs, A, B, made of any suitable material—30 such, for instance, as wood or metal. These limbs are rectangular at their free ends, and are marked with a scale of inches along one or both sides, and, if desirable, on one or both edges. The meeting ends of the limbs A, B 35 are oblique to the length of the limbs. As here shown, they extend at an angle of forty-five degrees to the length of the limbs. They are connected by a hinge, C. The leaves of this hinge may be secured to the limbs of the 40 rule in any suitable manner, as, for instance, by rivets or other like means, and a pintle passes through them to hold them in place,

and the ends of this pintle and of the leaves of the hinge are so shaped that they correspond with the inner and outer ruling-edges of the square—that is, at the meeting angle on the inside a right-angled recess is formed in the end of the hinge, so that it becomes a continuation of the inner straight edges. Likewise the outer end of the pintle is beveled to an edge to coincide with the outer edges of the rule. The limbs of the rule may be folded over, one on the other, or extended into the same plane at right angles to each other, so as to form a square. Said limbs have parallel sides throughout their lengths.

It will be seen that by my improvement I produce an article which may be used as a rule or a square, and which is of very cheap and simple construction.

I am aware that a folding square has been made consisting of two parts hinged together, so as to fold down flat upon each other and to stand at right angles when opened. In that device, however, the arms are widened at the joint, so that the interior inner straight edges do not intersect, and hence do not form and cannot be used as a square.

In my device the inner edges intersect at right angles, the apex of the angle being formed in the end of the hinge, as before described.

What I claim as my invention, and desire to secure by Letters Patent, is—

A folding square consisting of two blades connected by a miter-joint, so as to fold one upon the other, the inner straight edges being continued to their point of intersection, substantially as described.

LUDWIG HIRSCH.
